CARBONATED BEVERAGE DISPENSER

Rodrigo Lopez-Fabrega, Norwalk, and George L. Schick, Georgetown, Conn., assignors to National Distillers and Chemical Corporation, New York, N.Y., a corporation of Virginia

Filed Mar. 11, 1966, Ser. No. 1,423

Term of patent 14 years

(Cl. D2—3)

We claim:

The ornamental design for a carbonated beverage dispenser, as shown.
